Koscherak Bros. Inc., New York, N. Y., a corporation of New York

Application January 21, 1942, Serial No. 105,347

Term of patent 7 years

To all whom it may concern:

Be it known that I, Charles L. Fordyce, a citizen of the United States, residing at New York city, county and State of New York, have invented a new, original, and ornamental Design for a Cocktail Glass or Similar Article, of which the following is a specification, reference being had to the accompanying drawing, forming a part thereof.

Fig. 1 is a front perspective view of the cocktail glass or similar article, showing my design;

Fig. 2 is a side elevational view;

Fig. 3 is a side elevational view showing the side opposite the side illustrated in Fig. 2; and

Fig. 4 is a rear elevational view thereof.

The characteristic feature of the design is shown in full lines.

I claim:

The ornamental design for a cocktail glass or similar article, as shown and described.

CHARLES L. FORDYCE.
